UNITED STATES PATENT OFFICE.

WILLIAM W. SMITH, OF JERSEY CITY, NEW JERSEY.

SAMPLING DEVICE.

Application filed May 4, 1922. Serial No. 636,772.

This invention relates to means for sampling and observing or testing the character of liquid withdrawn from a source containing at least two liquids of different characters and discharging at a remote point.

The invention aims to provide means whereby the character of liquid being discharged at such remote point can be readily determined at a distance from the discharge point.

An embodiment of the invention is illustrated in the accompanying drawings in which Fig. 1 is a fragmentary cross-section through a portion of a ship showing a pump for discharging the bilge water overboard and discharging the oil separated from the bilge water into a storage tank and having my sampling device connected therewith;

Fig. 2 is an enlarged view illustrating an embodiment of the sampling device;

Figs. 3 and 4 are diagrammatic views illustrating different applications of my device.

Referring to the drawings, 10 represents conventionally a bilge pump which is connected by pipes 12 and 14 which lead to a suitable settling tank, not shown, or to the compartments in a ship containing a mixture of oil and water. Fuel oil or lubricant oil frequently collects in the hold of a ship and this mixture is sometimes drained into settling tanks or is pumped directly from the hold through suitable piping and discharged overboard. It is wasteful to discharge this oil with the water and also contaminates the surface of the water. This is particularly true in the case of vessels navigating small rivers and harbors, and there is a considerable agitation on the part of authorities to prevent the discharge of oil from ships.

In Fig. 1, I have shown the discharge pipe 16 connected to the pump 10 and with a riser 18 connected with a branch 20 adapted to discharge the liquid overboard, this pipe being provided with the control valve 22. The riser 18 is connected with a pipe 24 leading to a tank 26 adapted to store the oil pumped from the source containing oil and water, the pipe 24 being provided with a control valve 28.

In Fig. 1, I have shown a pet cock 30 connected to the lower end of the pipe 18 and arranged to discharge liquid into the sampling receptacle 32 when the pet cock is open. The receptacle 32 is carried by a

pipe 34 having a valve 36 which in turn is connected with a pipe 38 leading to the pipe 12 connected to the suction side of the pump. As thus arranged it is apparent that when the pump is operating, liquid will be drawn through the pipes 14 and 12 and discharged through the pipes 16 and 18 either to the tank 26 or overboard by way of pipe 20 according to the setting of valves 22 and 28. With the valve 22 closed and the valve 28 opened it is clear the liquid will be discharged into the tank 26 and vice versa. With the valve 28 closed and valve 22 opened the liquid will be discharged overboard.

My sampling device enables the operator near the pump to determine the character of liquid being pumped. It being apparent that by opening the pet cock 30 a portion of the liquid can be permitted to drip into the receptacle 32. And the liquid so collected therein can be observed by the pump operator or other attendant. If the sample shows that oil is being pumped, the valve 22 will be closed, and on the other hand, if the sample shows that water is being pumped, the valve 28 will be closed. After sufficient liquid has collected in the receptacle 32, the valve 36 can be opened and thus permit the liquid to return to the suction side of the pump by way of pipe 38 as will be understood. By properly adjusting the pet cock 30 and the valve 36, the liquid can continuously drip from the pet cock into the receptacle 32 so that the pump operator or other attendant can easily determine at any time what character of liquid is being pumped.

The vessel 32 may be of sheet metal and provided with a glass or other transparent window 33 or in some instances could be made entirely of glass or similar transparent material to permit observation of the liquid therein.

In Fig. 3, I have shown the pump 10 connected with a discharge riser 18 and have shown a branch 31 connected therewith to which the pet cock 30^a is secured. The sampling device 32 is located below the pet cock and connected by a branch 38^a with the pipe 12 connected to the suction side of the pump.

Fig. 4 shows diagrammatically the application of the device to any pipe line in which there is a flow of liquid and where the sampling device 32 is installed at a point above the ultimate storage or delivery of the liquid. 40 represents a pipe coming from the source

of liquid and 42 a pipe connected therewith leading to the point of delivery and having a valve 44 to regulate the flow. With this arrangement a pet cock 30^b is located in a branch pipe 46 connected to the supply pipe 40 and is adapted to deliver the sample of liquid into the receptacle 32 carried by a branch pipe 48 having a regulating valve 50 therein and connected with pipe 42 as shown.

With this arrangement when liquid is flowing through the pipe 40 and a sample is required, valve 44 is slightly closed and the pet cock 30^b opened permitting liquid to flow through the branch 46 and into the test receptacle 32. The valve 50 is opened and permits the sample withdrawn to flow by way of pipe 48 to the discharge line 42.

From the above it will be seen that my sampling device permits of selectively controlling the discharge of liquid from a source containing liquids of two or more specific gravities, and provides means whereby the character of the liquid being discharged at a remote point can be readily determined by observation of the liquid contained in or passing through the sampling receptacle.

The device may be used in various installations where it is desirable to test or observe the character of liquid being discharged and is particularly useful on board ship; as by its use I can prevent fuel oil being discharged overboard when the water is completely removed from either the settling tank or the hold.

From the foregoing it will be perceived that my invention provides means whereby the character of liquid being discharged or circulated can be readily determined by observation, and that if desired a sample of the liquid can be withdrawn from the device and tested or analyzed. In dark locations the attendant can roughly ascertain whether oil or water is flowing by merely inserting a finger in the receptacle and noting the "feel".

Or he can detect the different kinds of liquids flowing through the receptacle by their odor. Thus it is apparent that the character of liquid can be determined by the operator using either of the senses of sight, touch or smell, and in fact the sense of hearing can be trained to detect the difference between dripping oil and dripping water.

While I have described with great particularity the embodiment of the invention herein shown, and have illustrated the application of the device in connection with a discharge pump used on board ship, it is not to be construed that I am limited to such use, nor am I limited to the construction and arrangement shown, as variants may be adopted without departing from the invention as defined in the appended claims.

What I claim is:

1. In combination with the hold of a ship, a pump adapted to withdraw a mixture of bilge water and oil from said hold, an oil storage receptacle, piping connecting the latter with the pump and including a valve controlled branch pipe for discharging the water overboard, and means for withdrawing a sample of the liquid from said piping for observation and means for returning the sampled liquid to the suction side of the pump.

2. An apparatus for recovering the oil contained in the bilge water of a ship including in combination a pump, an oil storage tank, a pipe connecting said pump with said oil storage tank, a branch in said pipe for discharging bilge water overboard, valves for controlling the flow of liquid to said tank and through said branch, means adapted to receive a sample of liquid withdrawn from said pipe and means for returning such sample to the suction side of the pump.

In witness whereof, I have hereunto signed my name.

WILLIAM W. SMITH.
